PROCESS OF HARDENING CAMS

Donald J. Campbell, Spring Lake Township,
Ottawa County, Mich., assignor to Campbell,
Wyant & Cannon Foundry Company, Muskegon
Heights, Mich., a corporation of Michigan

Application June 19, 1933, Serial No. 676,467

1 Claim. (Cl. 148—10)

This invention relates to a process of hardening and is made use of particularly in hardening cams on cam shafts which are cast integrally with the shaft from a suitable composition cast iron.

5 Cam shafts, in conjunction with cams thereon, are used in internal combustion engines for operating the valves; and these cams are subject to severe wear and must be of a hard and durable character. Previously, cam shafts have been 10 largely made of a suitable grade of steel, forged to shape, and thereafter subjected to a hardening operation which hardens only the surface of the cams. This hardening operation, involving as it does the use of high degrees of temperature, is not only rather long and costly, but the shafts are subjected to danger of warping with a resultant loss of complete forged and heat-treated shafts, thus resulting in high cost of production. It has also been contemplated that the 15 cams on cast iron cam shafts might be hardened in the operation of casting by placing chills in the mold against which the iron of the cams would come when the mold was poured to cast the shaft. This has proven quite successful. The 20 time and labor consumed in setting the chills in the mold is an item of expense, however, slowing down production and increasing molding costs which the present invention eliminates.

In the present invention the cams, which are 25 cast integrally with the shaft, are each successively heated in a manner to rapidly raise the temperature of the cams to a degree sufficiently high to combine a high percentage of the carbon therein and then cooling the heated cam with 30 a greater or less degree of rapidity in accordance with the degree of hardness desired. That portion of the cam to be hardened is heated to substantially a red color, or above its critical point, and is then released from the heating apparatus and is either subjected directly to the cool atmosphere, which causes the cam to rapidly cool, or air at a lower degree of temperature than the atmosphere, or even at atmospheric temperature, may be blown over the cam and shaft to 35 more rapidly cool the same, producing a hard and an exceedingly durable, wear resisting cam structure. After the cams on a shaft have been thus heat treated or hardened, the cams are finished by a grinding operation.

40 An understanding of the invention may be had from the following description, taken in connection with the accompanying drawings, in which,

45 Figure 1 is a plan view of a machine for carrying out the cam hardening process of my invention.

Figure 2 is a front elevation thereof.

Figure 3 is an end view at the left-hand end of Figure 2.

Fig. 4 and Fig. 5 are transverse sections through the machine illustrating the cam holding heating electrodes in their operative and released positions, respectively.

Fig. 6 is a fragmentary longitudinal vertical section through one end of the cam shaft holder located at the left-hand end of the machine. 10

Fig. 7 is a transverse vertical section through the carriage which carries the cam holding and heating electrodes, and

Fig. 8 is an enlarged elevation illustrating the manner in which each cam is subjected to heating electrically to raise the temperature thereof. 15

Fig. 9 is an enlarged elevation illustrating the manner in which the cam is subjected to heating electrically when the electric current is passed from side to side of the cam and not through 20 the shaft.

Like reference characters refer to like parts in the different figures of the drawings.

A description of the preferred construction and operation of the machine shown in the drawings will disclose the manner in which the process is performed. In construction, an elongated supporting bed 1, at its upper side is equipped with guide and holding plates 2 bolted in place and lying lengthwise of the bed at both the front 25 and rear of the upper side thereof. At one end of this bed a fixture is secured comprising a post 3 which has a base with edge portions extending underneath the holding plates 2, at the upper end of which is a sleeve 4. At the other end of 30 the elongated support 1 a carrying member 5 is adjustably secured whereby the same may be adjusted to different positions along the bed 1 by releasing the plates 2, shifting the member 5 to a desired position and then tightening the bolts 40 to hold it securely in place. On this member 5 a support 6 is slidably mounted which at its upper end, is equipped with a sleeve 7 similar in substantially all respects to the sleeve 4 at the 45 upper end of the support 3. The movement of the slidable support 6 lengthwise of the member 5 is controlled by a lever 8 pivotally mounted at one end of the part 5 and extending through an opening in the lower portion of the support 6, the free end of the lever 8 extending in front of 50 the machine so that the operator thereof may engage the same with his hip and by moving side- 55 wise carry the support 6 with the connected sleeve 7 and the parts mounted thereon to the left (Figs. 1 and 2). Normally this free slidable

support 8 will be moved inwardly toward the right, there being connected therewith a bar 9 to which one end of a heavy coiled tension spring 10 is secured the other end thereof being secured 5 to the part 5, whereby on turning the lever 8 to the left spring 10 is stretched.

At the inner ends of both of the sleeves 4 and 7 a chuck 11 is mounted, each of which at its inner end is provided with a tapering bore 12, 10 one of said portions 12, namely, the one at the left hand end of the machine, being knurled as shown in Fig. 6. The chucks 11 are rotatably mounted on the respective inner ends of the sleeves 4 and 7, suitable anti-friction bearings 13 15 being disposed between each chuck and its carrying sleeve; and the sleeve 4 at the left-hand end of the machine is provided with a collar 11a in which radial openings spaced from each other are made for the reception of a rod to manually 20 turn the chuck 11, as is evident.

A rod 14 is slidably mounted lengthwise of the sleeve 7 and is normally pressed inwardly by a coiled spring 15 as shown in Fig. 6, the inner end thereof being adapted to contact with an 25 end of a cam shaft located in the chuck. An electric conduit 16 is connected to the outer end of the rod 14 of the fixture at the left-hand end of the machine.

It is apparent that a camshaft 17, on which 30 there are located in spaced apart relation a plurality of cams 18, may be disposed between the two holding chucks 11 by operating the lever 8 to the left placing the camshaft in position and then releasing the lever. The reduced end portions 11a of the cam shaft 17 engage with the ends of the contact rods 14. And from the rod 14, which extends lengthwise of the sleeve 4, an electric cable 19 may lead, as shown.

A rack 20, having rack teeth at its upper side, 40 is located lengthwise of the bed 1 and substantially centrally thereof. Over this a supporting carriage is mounted including a flat plate 21 which slides underneath the retaining guide plates 2 and upon the upper side of the bed 1. 45 Integral with the plate 21 is a housing 22 in which a pinion 23 is housed, meshing with the rack 20 and having a shaft 24 which extends outwardly to the front side of the machine, and is equipped with a wheel 25 to turn the pinion and thereby 50 move the carriage and attached parts to different positions in the length of the machine.

The carriage also includes two upwardly extending and spaced vertical supporting posts 26 and 27. A lever 28 is located between the posts 55 toward their lower ends and pivotally mounted thereon, the forward end carrying an electrode 29, preferably of copper, connected with which is an electric conduit 30. The lever 28 is pivotally mounted between its ends on the posts 26 and 60 27 at 31.

At the upper ends of the posts 26 and 27 and between the same is a second lever 32, pivotally mounted between its ends at 33, and at its front end and on the underside thereof carrying an electrode 34 preferably of copper which is insulated from the lever 32, on which it is mounted, by suitable insulation 35.

An operating handle 36 is pivotally mounted 70 at its lower end on the rear end of the lever 28. A link 37, adjustable as to length is pivotally connected at one end to the operating handle 36 a short distance above the rear end of lever 28 and at its other end has pivotal connection with the rear end of the lever 32, whereby on pulling 75 the handle 36 to a vertical position, as in Fig. 4,

the two electrodes 34 and 29 are brought toward each other and may clamp a cam shaft and a cam thereon between them as shown; and on throwing the operating handle 36 backward to the position shown in Fig. 5, the electrodes 28 and 29 are moved away from the cam shaft 17 releasing the same. An electric cable 38 connects with the electrode 34 as shown in Fig. 2.

In operation, after a cam shaft has been placed between the holding chucks 11, the wheel 25 is moved so as to bring the electrodes 29 and 34 opposite the selected cam 18 to be treated. In practice the hardening process will ordinarily begin at the cam nearest one end of the shaft, and will then be performed successively upon the 15 cams until the one nearest the other end of the shaft is finished. The knurled character of the chuck at the left end of the machine causes the shaft to turn with such chuck, and by inserting a rod in an opening in the annular flange 11a the cam shaft may be turned such that the cam selected for the hardening process is positioned towards the electrodes from the shaft, whereby on moving the operating handle 36 from the position shown in Fig. 5 to that shown in Fig. 4 the opposite sides of the cam 18 bear against the inner inclined sides of the jaws at the lower end of the electrode 34 as best shown in Fig. 8; while the lower arc-shaped side of the cam 18 bears against the upper side of the electrode or 30 anvil 29.

When the electrodes thus contact with and clamp against a cam 18 on the shaft electric current is passed through the cam and serves to rapidly raise the temperature of the cam to a 35 temperature above the critical or approximating 1000° F. or more. The operator can judge by the color which is produced when approximately the desired temperature has been reached.

The operating handle 36 is then turned to the 40 position shown in Fig. 5 thus automatically stopping electric current flow and releasing the cam. Upon the cam being released, which has been heated, either the direct lower temperature of the surrounding atmosphere will act to rapidly 45 lower the temperature, or air may be blown upon the cam to more rapidly lower the temperature. For succeeding cams the operation is repeated. Upon releasing the electrodes from a selected cam, the wheel 25 is moved to bring the electrodes to the next adjacent cam, the shaft is turned by turning the chuck 11 at the left-hand end of the machine to properly position the cam which is to be heated, and then the lever 36 is moved from the position shown in Fig. 5 to that 55 shown in Fig. 4. The treatment of all of the cams on a cam shaft is very rapid and in a cam-shaft having ten cams, as shown in Fig. 1, the entire heating of all of the cams does not necessarily consume over thirty seconds. 60

The degree of hardness of the cams may be controlled by the rapidity with which the temperature of the cams is raised and the rapidity with which the temperature is reduced after electric heating. It may be reduced, as said before, 65 by blowing cold air on them or cooled by a desired temperature water or other fluid.

The process described is rapid, efficient and economical. The cams are cast in the first instance, together with the shaft, as iron castings, 70 cleaned of sand and loose scale, taken to the machine which is used to electrically heat the same, raised to a high degree of temperature, approximating 1000° F. or more, and then cooled rapidly, it being understood that the rate of heat- 75

ing and cooling may be controlled and the faster the heating and the faster the cooling takes place, the harder the cams will be; likewise, the higher the temperature, the harder they will be.

5 While I have described my invention as carried out with an electrical heating apparatus, I wish it understood that the heating apparatus is not a part of this invention and that any method of heating the cams can be employed without 10 departing from the invention.

I claim:

The process of heat treating a cast iron cam shaft which consists in separately heating the cams on said cam shaft by passing electricity through the cams in two paths so as to symmetrically heat the cams, said path starting near the highest point of the cam but on opposite sides thereof, and then cooling the cams.

5 DONALD J. CAMPBELL. 10
